UNITED STATES PATENT OFFICE.

ARTHUR J. ADAMS, OF HUNTINGTON PARK, CALIFORNIA.

SUBMERGED TURBINE.

Application filed June 16, 1927. Serial No. 199,338.

The invention aims to provide a new and improved turbine to be operated by the current in a stream or river, the construction being such that the main working parts are all 5 submerged, so that there is no danger of injury from surface waves, for instance, in storms.

With the foregoing in view, the invention resides in the novel subject matter herein- 10 after described and claimed, the description being supplemented by the accompanying drawing.

Fig. 1 is a side elevation partly in section of a turbine constructed in accordance with 15 my invention.

Fig. 2 is a top plan view partly broken away and in horizontal section.

Figs. 3 and 4 are detail elevations as indicated by the lines 3—3 and 4—4 of Fig. 1.

20 In the drawing above briefly described, the numeral 5 designates any desired frame structure. Rotatably supported by this frame structure, in appropriate bearings 6 and 7, is a vertical shaft 8 carrying upper and lower 25 hubs 9 and 10. A plurality of rectangular frames 11 are disposed in planes radiating from the shaft 8, and the upper and lower corners of said frames, that is the inner corners thereof, are provided with extensions 30 12 and 13 which are secured to the hubs 9 and 10, by bolts 14 and 15. Each frame 11 is preferably provided with a diagonal brace rod 16 and the several frames are tied in suitably spaced relation, by rods or the like 17 and 18.

35 Any desired number of plates 19 are pivotally hung in each frame 11, between opposed side bars of the latter. At one side of the shaft 8, these plates always assume vertical positions as seen at the right of Figs. 1 and 2 40 and in Fig. 4, so that the flowing water (indicated by the arrows A) will force against these plates and rotate the wheel structure formed by the frames 11 and associated parts. As the plates reach positions at the opposite 45 side of the shaft 8, however, they swing to horizontal positions as seen at the left of Figs. 1 and 2, and in Fig. 3, and hence they will merely cut through the water, without appreciable resistance.

50 Preferably, the upper edge of each plate 19 is provided with a tubular bead 20 and the opposite edge is formed with a similar bead 21. Rods 22 and 23 pass through these beads and project beyond them, the projecting ends 55 of each rod 22, passing through openings in side bars of the frame 11, so as to pivotally

mount the plate 19. The projecting ends of the rod 23 however, constitute stops which are adapted to strike the aforesaid frame bars to limit the movement of the plate 19 when it reaches its vertical position. In addition to performing the functions of pivotally mounting the plates and acting as movement limiting stops, it will be understood that the rods 22 and 23 also serve as effective stiffeners for the plates, permitting the use of thin sheet metal in the construction of the latter.

If desired, power may be taken directly from the shaft 8. In the present showing however, I have disclosed a counter-shaft 24 provided with a pulley 25, and a suitable belt 26 is engaged with this pulley and trained around the upper portion of the wheel structure. Suitable guides, such as those indicated at 27 may be provided on the frames 25 11, for the belt 26. Due to the relative sizes of the wheel structure formed by the frames 11 and associated parts, and the pulley 25, the latter and its shaft 24 will of course be rapidly driven, even though the aforesaid 80 wheel structure may rotate slowly.

As excellent results are obtainable from the general construction herein disclosed, it may well be followed. However, within the scope of the invention as claimed, variations 85 may of course be made.

I claim:

1. A submerged turbine comprising a shaft, a plurality of rectangular frames disposed in planes radiating from said shaft and 90 connected with the latter to provide a wheel, a plurality of plates between opposed side bars of said frames and pivoted to said bars, said plates being movable to vertical positions at one side of the shaft and to horizontal 95 positions at the other side thereof, whereby the plates may receive the pressure of the water current at said one side of the shaft but must cut through the water at said other side thereof, the plates being formed of sheet 100 metal with tubular beads along parallel edges, the pivot of each plate being formed of a rod passing through one bead thereof, the movement limiting means for each plate consisting of a second rod passing through the 105 other bead and projecting therefrom to strike said bars.

2. A submerged turbine comprising a shaft, a plurality of rectangular frame disposed in planes radiating from said shaft and 110 connected with the latter to provide a wheel, a plurality of plates between opposed side

bars of said frame and pivoted to said bars, said plates being movable to vertical positions at one side of the shaft and to horizontal positions at the other side thereof, whereby the plates may receive the pressure of the water current at said one side of the shaft but must cut through the water at said other side thereof, upper and lower rods secured respectively to the upper and lower edges of said plates, the ends of said rods

the projecting ends of said upper rods passing through openings in the side bars of the frame whereby the plates are pivotally supported, the projecting ends of said lower bars being adapted to strike the side bars of the frame thereby forming stops to limit the pivotal movement of the plates in one direction.

In testimony whereof I have hereunto affixed my signature.

ARTHUR J. ADAMS.
